UNITED STATES PATENT OFFICE

JOSEPH PICARELLI AND ROBERT DRAGHI, OF BROOKLYN, NEW YORK

BALANCER RING

Application filed February 1, 1928. Serial No. 251,015.

This invention relates to a balancer ring for cooking utensils, such as pots, pans and kettles, as disposed upon a heating means, as a stove, grate or the like.

Such utensils are usually made of thin metal which upon being subjected to intense heat, warp, buckle and bulge at their bottoms from their initial level, producing a rocking effect, rendering their use less effective and even dangerous.

It is therefore a prominent object of the present invention to provide a balancing ring to be disposed intermediate the heating means and bottoms of such utensils, whereby a firm and secure seat at their bottom edges is secured wholly irrespective of the condition of the bottom surface.

A further feature is in the provision of means for retaining the ring in an adjusted position centrally of the heating means, as for instance the grid of a gas stove.

Further objects are to provide a ring of light weight, suited in size to the cooking utensil with which it is used, easily movable as may be desired, and which is inexpensive to manufacture.

These several advantageous features are accomplished by the novel design and construction of parts hereinafter described and shown in the accompanying drawing, constituting an essential portion of this disclosure, and in which:—

Fig. 1 is a top plan view of an embodiment of the invention, illustrating its application.

Fig. 2 is a fragmentary transverse sectional view of the same, drawn to an enlarged scale, the section being taken on line 2—2 of Fig. 1.

Fig. 3 is a similar sectional view showing a slightly modified form of the ring section.

Fig. 4 is another like view showing a further modification. In dotted lines in this figure a frying pan or other utensil is shown with its base resting on the head of the ring.

The embodiment of the invention as shown in Figure 1 rests on the usual series of radial bars 5 of a conventional gas stove, these ribs being connected near their inner ends by bands 6, similar arrangements being common in electric ranges and like heating means, on

which may be placed any ordinary form of cooking vessel 7.

The invention resides in the provision of a ring generically designated by the numeral 9, the same being composed, as shown in Figures 1 and 2, of a narrow outstanding base flange 10, from which rises a vertical wall 11 leading to a curved bead 12, the inner side of which blends by a curved wall 13 into an inreaching flange 14. In dotted lines in Fig. 2 another form of utensil is shown.

At two opposite points the inner flange 14 is omitted and extending radially inward from the curved surface 13 are arms 15 adapted to seat, together with the flanges 10 and 14 upon the bars 5, these arms having at their inner ends downreaching lugs 16 to straddle opposed bars whereby the ring is held against accidental displacement.

In the modified form illustrated in Figure 3, an outer base flange 20 supports a vertical wall 21 leading to a bead 22 blending into a downwardly inclined wall 23 terminating in a short vertical inner wall 24 having an inreaching base flange 25.

The flange 25, like the flange 24, is cut away at two opposite sides and lugs 26 extended down from the wall 24 to engage the bars 5.

It is to be noted that both these devices can be made of sheet metal die cut and pressed into the desired shape, and that the curved lower edge of the cooking utensil, of suitable diameter, will seat upon the elements 13 or 23, and be firmly held upright and stationary over the center of the heating appliance, notwithstanding any inequalities in the bottom of the vessel.

In the modification shown in Figure 4, the device is shown to consist of a solid ring 30 having a raised annular bead 31 and a concave inner surface 32 to receive a vessel, two opposed extensions 33 being provided with downreaching lugs 34 to maintain the device in position.

As can be seen, all danger of tipping and one side frying is eliminated, a low frying pan being held level by its use; it is also clear that the device is sufficiently deep to engage the vessel placed thereon, preventing it from

becoming inadvertently displaced or overturned, while the ring itself is effectively anchored, not being slideable in any direction, thereby avoiding possible accidents.

5 While certain preferred embodiments of this device have been shown and described, it will be understood that changes in the form, arrangements, proportions, sizes and details thereof may be made without departing from 10 the scope of the invention as defined in the appended claim.

Having thus described our invention, what we claim as new and desire to secure by Letters Patent, is:—

15 A ring disposable over a heat source, and comprising a raised hollow bead to conformably receive the lower peripheral edge of a cooking vessel, base flanges on said ring to seat upon a heater, a pair of opposed inreaching arms on said ring, and means at the ends 20 of said arms to retain the ring in adjusted position, and comprising downreaching lugs adapted to hold the ring against accidental displacement.

25 In testimony whereof we have affixed our signatures.

JOSEPH PICARELLI.
ROBERT DRAGHI.
